UNITED STATES PATENT OFFICE.

CHARLES WESLEY HOWELL, JR., OF NEWARK, NEW JERSEY.

PROPELLER.

1,119,826.

Specification of Letters Patent.

Patented Dec. 8, 1914.

Application filed July 3, 1911. Serial No. 636,763.

To all whom it may concern:

Be it known that I, CHARLES WESLEY HOWELL, Jr., a citizen of the United States, residing at Newark, in the county of Essex and State of New Jersey, have invented certain new and useful Improvements in Propellers, of which the following is a specification, reference being had therein to the accompanying drawing.

10 My invention relates to improvements in propellers and more particularly, it has reference to aerial propellers having engaging surfaces which will act upon the air substantially throughout their area.

15 It is well known that a propeller draws air from the region before it and from the region surrounding its periphery and in so doing creates partial vacuums in these regions that are destroyed by atmospheric pressure seeking to maintain atmospheric equilibrium. The currents resulting from such phenomena are well defined in character and it is obvious that a propeller having 20 rotating and forward movement will act 25 upon these currents and give propulsive or tractive impulse, but it has been observed that much of the air is forced beyond the cutting edge and away from the engaging surface of the ordinary and usual form of 30 propeller blade before it is properly acted upon.

The usual form of propeller blade surface has been a slightly curved one and experience has shown that this surface does not 35 act wholly upon the air but mostly at a distance from the cutting edge or toward the rear. It was early assumed that a broad blade surface would give the most efficient results, but recent practice has proven that a 40 narrow blade is more efficient, the theory being that the narrow blade does not disturb the air unduly and cause a loss of efficiency.

In the new form of blade surface presented herewith the cutting edge as ordinarily 45 termed, has a negative angle. That is to say, the surface of the blade adjacent to the cutting edge is presented at an angle opposite to the angle of the blade as a whole and is preferably curved in cross-section and so 50 acts upon the atmospheric pressure current as to cause it to bend around the cutting edge and it is then drawn toward the engaging surface of the propeller blade by reason of the suction or vacuous condition caused 55 by the recessed side of the cutting edge. It is obvious therefore that the atmospheric

pressure current is encouraged to act quickly upon or to be acted upon quickly by the engaging surface of the blade near its forward edge thereby increasing the efficiency of the 60 blade due to the fact that the major portion of the engaging surface is actually brought into useful service.

In the accompanying drawings I have shown in Figure 1 a plan view of one form 65 of propeller illustrating an application of my invention. Fig. 2 is an edge view of the same looking upwardly at Fig. 1, Fig. 3 is an enlarged plan view in dotted outline illustrating one blade of the propeller and 70 showing cross sections of the same at five different points of the radius, and Fig. 4 is an end view looking from left to right at Fig. 3.

Looking at Fig. 1, the upper left and the 75 lower right edges, indicated by the reference characters 4 and 5, are the cutting edges of 80 blades of the propeller. As shown in Fig. 2 these cutting edges are not horizontal as are the rear edges of the blades when the propeller is mounted upon a vertical axis. It will of course be understood that the cutting edges may be made horizontal if desired but in that case the rear edges should be at an angle in order to allow for constructional variations necessary to compensate for differences in speed at different points along the 85 radius of the blade, or both the cutting edges and the rear edges may be at an angle to the 90 horizontal.

The cross section of the blade, indicated 95 by the reference character 6 nearest the axis of the propeller has a curvature of small radius, the radius of the curvature of the next cross-section indicated by the reference character 7 is slightly greater, and the radius of the curvature of each of the other cross-sections 8, 9 and 10 is greater as the tip of the blade is approached. This curvature at the cutting edge presents a negative angle throughout the entire length of each blade. This negative angle may be made more pronounced, and the width of the blade may be decreased, in the direction of the axis of the propeller. Under these conditions, the 100 atmospheric pressure current which is encountered more slowly near the axis than near the periphery of the propeller, is nevertheless subjected to similar action. That is to say, after the atmospheric pressure current has rounded the modified negative angle of the cutting edge near the periphery 105 110

of the blade it is acted upon by the entire surface of a rapidly moving broad portion of the blade at a modified angle of incidence or curvature, while the atmospheric pressure current which has rounded the abrupt negative angle of the cutting edge near the axis of the blade is being acted upon by the entire surface of a slowly moving narrow portion of the blade at an abrupt angle of incidence or curvature, thus equalizing conditions throughout the length of the blade.

The correct cross-section for the blade of the propeller is determined by the intended speed of rotation of the propeller and the intended forward speed of the propeller while rotating. In addition to the negative angle along the cutting edge of the blade of the propeller it has also been found to be of advantage to form the end or tip of each blade with a negative angle graduated along a line equally distant at all points from the axis of the propeller as indicated by the reference characters 11 and 12. This causes the atmospheric pressure current from the region surrounding the propeller to recess itself within the negative angle at the tip of each blade after which it is caught upon the broad engaging surface of the blade before it escapes.

30 Of course it will be understood that modifications may be made without departing from the spirit of the invention as set forth in the claims.

I claim:

35 1. A propeller having a blade portion with a cutting edge presenting a negative angle, said negative angle becoming more

abrupt in the direction of the axis of said propeller.

2. A propeller having a blade portion 40 with a cutting edge presenting a negative angle becoming more abrupt in the direction of the axis of said propeller, said blade portion of curved cross section decreasing in radius in the direction of its axis. 45

3. A propeller having a blade portion with a cutting edge presenting a negative angle, and a tip also presenting a negative angle.

4. A propeller having a blade portion 50 with a cutting edge presenting a negative angle, said blade portion of curved cross section and presenting a negative angle at its tip.

5. A propeller having a blade portion 55 with a cutting edge presenting a negative angle, and a tip also presenting a negative angle, said tip being equally distant at all points from the axis of said propeller.

6. A propeller having a blade portion 60 with a cutting edge presenting a negative angle becoming more acute in the direction of the axis of said propeller, said blade portion of curved cross section decreasing in radius in the direction of its axis, and increasing in area and decreasing in thickness in the direction of its tip. 65

In testimony whereof I affix my signature in presence of two witnesses.

CHARLES WESLEY HOWELL, JR.
